CALCULATING MACHINE

Jesse R. Ganger, Dayton, Ohio, assignor to The National Cash Register Company, Dayton, Ohio, a corporation of Maryland

Application July 26, 1937, Serial No. 155,595

16 Claims. (Cl. 197—132)

This invention pertains to improvements in tally strip feed mechanism for adding, listing, calculating, and combined typewriting and adding machines, and other machines of similar general character, said tally strip being used to obtain a duplicate record of items recorded on a primary work sheet.

The principal object of this invention is to provide an automatic tally strip feed mechanism which will not obstruct the operator's view of the primary work sheet carried by the platen. This object is achieved by storing the tally paper supply in the rear of the carriage, conducting it under the carriage in a chute, and then guiding it to a position where it may be struck by the type.

Another object of the invention is to provide disabling mechanism for the automatic tally paper feed and a hand operated feed which may be used whether the automatic feed is in use or disabled.

Another object of the invention is to arrange the tally feed mechanism so that the last printed line is visible to the operator and the entire printed portion may be torn off without advancing the paper feed.

Another object of the invention is to provide automatic means for moving the tally strip tearing knife away from the moving type on each printing operation, thus allowing the knife to be normally positioned beneath the printing line.

The invention as disclosed herein shows the tally strip feed mechanism mounted on the general type of machines shown and described in Letters Patent No. 1,197,276 issued to Halcolm Ellis on September 5, 1916, and Letters Patent No. 1,197,278 issued to Halcolm Ellis on September 5, 1916, but it is to be understood that the invention can be applied to other machines than those to which specific reference is made.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a part side elevation and a part vertical section parallel to the side of the tally roll feed mechanism as mounted in relation to the carriage bed and platen.

Fig. 2 is a plan view of the finger feed mecha-

nism and the storage bracket for the tally strip roll.

Fig. 3 is a part section and part elevation of the finger feed mechanism shown in Fig. 2, as indicated by the line 3—3, with part of the enclosing chute removed.

Fig. 4 is a side elevation of the printing segments, a vertical section through the platen, showing the end of the paper chute, the ink ribbon, the tally strip, the tearing knife and the primary work sheet.

Fig. 5 illustrates the disabling mechanism for the automatic feed, looking in the direction of the arrows at 5—5 in Fig. 6.

Fig. 6 is a front elevation of the parts shown in Fig. 1, showing the lateral disposition of the parts shown in Fig. 1. The printing segments have been removed.

Fig. 7 shows a modified construction of paper feed mechanism and means to disable it, and a modified form of tearing knife construction.

Fig. 8 is a plan view of the modified construction shown in Fig. 7 with the platen and ribbon removed.

Fig. 9 is a detailed view of the modified tally feed shown in Fig. 7 with the drive shaft and the knife mechanism removed.

Fig. 10 is the same as Fig. 9, with phantom showing of the hidden parts.

Fig. 11 is a side elevation of the manual tally feed knob and feed pawl.

Detailed description

Referring to Fig. 1, the frame 30 represents the machine to which the tally feed mechanism is attached, and which, for the purpose of illustrating this disclosure, is a listing-adding machine as described in Letters Patent No. 1,197,278, to which reference was made above. The carriage and its supports are not shown, but at 31 is shown the relative position of the roll platen. The tally strip storage roll bracket 32 is attached to the rear framework 30 out of the way of the operator's view. The tally strip roll 33 is mounted axially on studs 34 in such a manner that the tally strip 35 may be unrolled and inserted into a flat chute 36 which rests upon that part of the frame 30 beneath the carriage. The tally strip chute 36, after passing between the carriage and the frame, from the rear of the machine to a point below the front edge of the platen, turns upward 40 and comes to an end 37 just below the inking ribbons 41. The tally strip continues upward between the inking ribbons, past a tearing knife 39, and out of the machine. 55

The platen carries a primary work sheet 42. Between the tally strip and the primary work sheet is one of the inking ribbons, and between the tally strip and the type segments 38 there is 5 the other inking ribbon so that, as the type strikes, an impression is made through two ribbons at the same time, leaving a positive impression on the front of the tally strip, a negative impression on the back of the tally strip, and a 10 positive impression on the front of the primary work sheet.

Paper feed mechanism

Attached to the horizontal portion of the paper 15 chute is a finger push-feed device for moving the tally strip a distance of one line for each operation of the machine. An upper finger 43 and a lower finger 44 (Figs. 1, 2, and 3) are carried by a reciprocating sleeve yoke 45 (Figs. 2 and 3) 20 which surrounds the paper chute 36. The bottom of the yoke contains guide slots 46 (Fig. 2) to accommodate studs 47 (Figs. 1 and 2) projecting from the bottom of the chute 36, the length of said guide slots allowing and limiting the reciprocating motion of the yoke. The slots 46 and studs 47 also serve to keep the yoke from binding on the chute as the moving force is applied to only one of its sides. An opening 48 (Figs. 2 and 3) through the top and bottom of the chute is 25 made to expose the tally strip carried within and give opportunity for the fingers 43-44 to grasp it and move it. The opening 48 is long enough to permit the fingers 43 and 44 to reciprocate within it the full distance of the yoke's movement. The fingers are held yieldingly together 30 by flat springs 49 (Figs. 1, 2, and 3) with sufficient tension to move the tally strip when the yoke is moved. On reciprocating motion of the yoke 45, the drive for which will be explained 35 later, the constant gripping of the tally strip by the fingers 43-44 would also cause the tally strip to reciprocate. To release the gripping of the fingers after the forward motion of the yoke 45 is finished, the upper finger 43 is raised and held 40 away from the tally strip during the backward cycle of the reciprocating motion of the yoke 45, by a method which will now be described. The forward end 58 (Fig. 3) of the upper finger 43 has on either side outwardly projecting ears 60 45 (Figs. 2 and 3). The forward end 58 is inclined upwardly from front to rear, the inclination being shown best in Fig. 3. In both Figs. 2 and 3 the yoke and fingers are shown in their rear-most position. Upon the fingers 43-44 moving 50 forward with the paper gripped, the outwardly projecting ears 60 on the forward end 58 of the fingers 43 meet inwardly projecting ears 61 held by a tally strip retainer 62 and set parallel to ears 60. The tally strip retainer 62 is pivoted at 55 59, but is normally held against the tally strip by spring 63 (Fig. 2). Upon the forward or feeding movement of the fingers 43-44 the ears 60 pass under ears 61, which raises the tally strip retainer 62, against the tension of spring 63, thus 60 releasing the tally strip and permitting the free feeding movement. On the further forward movement of the yoke, the ears 60 pass from beneath ears 61 and the tally strip retainer falls to 65 normal position, holding the tally strip against the bottom of the chute and against rearward movement.

During the forward movement of the fingers, the tally strip is being fed forward. On the rearward movement of the fingers, the ears 60 are 70 carried over ears 61 by reason of their parallel

inclination and the finger 43 is raised, releasing the grip on the tally strip and allowing the forward movement of the strip to be retained. The ears 60 and 61 are so positioned that they pass one another near the extreme limits of their 5 relative movement; consequently the tally strip is moved in a forward direction only. At the end of the rearward movement of the fingers 43-44, the finger 43 is released when the ears 60 have passed beyond the ears 61 and snaps into engagement with the strip 35 under the action of springs 49.

The drive mechanism

A reciprocating drive link 64 (Fig. 1) from the 15 motor drive mechanism makes one up-and-down movement for each cycle of operation of the machine. For a further description of a motor drive mechanism of this type see U. S. Letters Patent 1,601,102 issued to F. W. Bernau September 28, 1926. This motion is delivered to lever 65 by stud 66. The lever 65 is rigidly attached at its forward end to shaft 67. Fastened to shaft 67 and turning first counter-clockwise and then clockwise during each cycle of operation is lever 20 68, which at its outer end has a stud 69 engaged in a cam slot 70. Cam slot 70 is cut in a plate 71 pivoted at its forward end to the supporting framework at 72 and to a tally feed drive link 73 at the other end. Counter-clockwise movement of stud 69 in the cam slot 70 causes upward movement of the link 73, while clockwise movement of stud 69 causes downward movement of link 73. Therefore, in one operating cycle of the machine, link 73 makes one complete up- 30 and-down movement.

Automatic tally feed

The link 73 at its upper end (Figs. 1, 4 and 6) is pivotally connected at 74 to lever 75 and lever 40 75 is fastened to shaft 76, which is thus rocked first counter-clockwise and then clockwise during an operative cycle of the machine. The shaft 76 (Figs. 4 and 6) has fastened thereon two arms 77 (Figs. 4 and 6) spaced the width of the tally 45 paper strip and joined at their outer ends with a tearing knife 39 thus forming a yoke frame, which is shown in Fig. 6, at the rest interval between operations of the machine. In Fig. 4 two positions of the knife 39 and the arms 77 are 50 shown. The solid line position represents the position when the shaft 73 is down and the machine at rest between operations. The dotted line in Fig. 4 represents the arms and tearing knife when the shaft 73 is raised and the machine in operation. The purpose of raising the tearing knife during the operation of the machine is to remove it from the path of the type segments 38 as they are being thrown rearward toward the platen. The knife, when at rest, being 55 positioned so as to render the last amount printed on the tally strip visible without turning the strip forward, would otherwise be struck. The strip can be torn off with the last printed matter appearing thereon without turning the strip forward, as the tearing edge of the knife is below the printing line when the machine is at rest. It is immaterial whether the knife be raised or lowered during the printing operation, just so it is removed from the path of the moving type. 60

Near the upper end of link 73 (Fig. 1) is a forwardly projecting cam 90 which acts on stud 91. As the link 73 is raised, the upper inclined edge of cam 90 engages the stud 91, carrying it forward. Stud 91 is fastened to an arm 93 75

mounted on a loose sleeve 94 around shaft 76. On the end of the sleeve 94, opposite arm 93, is a downwardly extending arm 95 (Figs. 5 and 6) carrying a pin 96 projecting into a slot 97 (Fig. 5) cut in a link 98 (Figs. 1 and 5), which link is connected with the yoke 45 by a stud 99 (Fig. 2) and which imparts the reciprocating motion to said yoke. The backward and forward motion of arm 95, communicated through sleeve 94 from the cam-operated stud 91 and arm 93, causes pin 96 to play back and forth in the slot 97 unless a hook 89 (Fig. 5) pivoted to link 98 engages said stud 96 and anchors it against play. Movement of arm 95 by up-and-down motion of link 73 will then reciprocate link 98 and impart the necessary motion to yoke 45 to move the tally strip forward. By the time the point 92 of the cam 90 and stud 91 have engaged, a lever 93, to which stud 91 is attached, has been rocked clockwise to the limit of its movement as governed by slots 46 and stud 47 (Fig. 2). The arc described by stud 74, on continued counter-clockwise movement of lever 75, would tend to carry the cam 90 still farther to the left and impart a forward motion to stud 91 independent of the upper edge of the cam, and thus strain the parts. Therefore, to hold the stud 91 from further forward movement after passing point 92, the lower edge of the cam is inclined to the rear to compensate for the forward movement of the plate 90.

The tally strip feeding occurring only on the forward motion of the yoke 45, and that motion occurring first in the cycle of machine operation, the tally strip is advanced before the printing takes place.

Disabling of the automatic tally feed

Disengagement of the hook 89 from stud 96, 40 prevents the operation of the machine advancing the tally strip. This tally feed disabling device is moved to engaged and disengaged position by means of finger-operated levers 100 and 101 (Fig. 5). Fig. 5 shows the hook 89 engaged and 45 the feed mechanism operative. To disengage the hook, lever 101 must be caused to turn counter-clockwise slightly, which, through link 103, lifts the hook 89 from stud 96. A latch lever 100 is pivoted to arm 95. A pin 107 on latch lever 100 50 extends into a kidney-shaped cam slot 108 in lever 101. With the pin in the rear portion of the slot, as shown in Fig. 5, any attempt to turn lever 101 counter-clockwise will result in hump 110 of cam slot 108 giving a radial thrust to latch lever 100 through pivot 102 in the direction of pin 107. Since there can be no motion radially 55 to pivot 102, the latch lever effectively locks lever 101. If a turning motion is imparted to latch lever 100 in a counter-clockwise direction, the pin 107 is raised over the hump 110 and the lever 101 is permitted to turn counter-clockwise. A secondary result of turning lever 100 counter-clockwise is to stretch spring 106, which pulls hook 89 from stud 96 by causing lever 101 to turn 60 counter-clockwise. To again engage stud 96 and hook 89, lever 101 is turned clockwise manually. The stretching of spring 106 imparts clockwise motion to lever 101 and pin 107 is cammed back to the position shown in Fig. 5. The pivotal connection 109 has a slight play to compensate for the camming of lever 101 by pin 107 riding over hump 110.

Hand operated tally feed

75 A knob 120 (Fig. 1) is securely fastened to

shaft 121 (Fig. 1), which shaft is rotatably mounted in the right side of the cabinet and held in position by collars 122. The inner collar 122 is fast on the shaft 121 and carries on its inner end a four-petaled cam disc 123 which turns with the knob 120. A cam follower 124 engages the edge of the cam disc, said cam follower being mounted at the end of a lever 125 pivoted to a stud 126 on the inside of the cabinet 30. The opposite end of lever 125 is hooked to stud 127 on the same arm 93 as stud 91. No matter whether knob 100 is turned clockwise or counter-clockwise, the cam follower 124 is forced away from shaft 121 and lever 125 is rocked counter-clockwise, which, through lever 15 93, sleeve 94, arm 95 and link 98, moves the tally strip feeding means forward in the same manner as does the upward motion of link 73. Spring 128 keeps the cam follower 124 in contact with the cam and also serves to hold the cam follower 20 in the position shown in Fig. 1 unless disturbed by rotation of the knob 100 or movement communicated to the lever 125 by motor driven movements of arm 93.

Modified construction

25

Figs. 7, 8, 9, 10 and 11 show modifications of construction for certain of the elements of this invention.

Modified form of tear off knife mechanism

30

In Fig. 7 are shown a platen 31, a work sheet 42, an inking ribbon 41, and a tally strip 35, together with a modified form of paper feed, knife actuating mechanism, and paper feed disabling means. The link 73 (Fig. 7), making one up-and-down movement at each machine operation, turns arm 130 (Figs. 7 and 8) and its shaft 131 first in a clockwise and then in a counter-clockwise direction. The inner end of shaft 131 is pivoted in a bracket 132 (Figs. 7 and 8), a flange of which is anchored to the framework of the machine. Bracket 132 and a similar bracket 133 (Fig. 8) are spaced apart to accommodate a yoke 137 pivotally mounted to the forwardly extending arms of brackets 132 and 133 by studs 139. The yoke 137 has rearwardly extending arms 136 slotted to receive two pairs of studs 135 and 143 attached to forwardly extending arms 162 of a tearing knife 138. The slots in arms 136 are long enough to permit forward and backward play of the studs 135 and 143, and therefore of the tearing knife 138 to which they are attached. As the only motion of the tearing knife in relation to the yoke 137 is radial to pivots 139, the two move together when the yoke 137 is rocked clockwise and then counter-clockwise in each machine operation. The purpose of this clockwise and counter-clockwise movement of the yoke 137 is to carry the tearing knife down to a position below the path of movement of the type segments during the printing operation. The purpose of the forward and backward play of the tearing knife is to keep it from striking the inking ribbon 41 as it is rocked downward. The yoke 137 and tearing knife 138 are shown at the rest or home position in Fig. 7. On downward or clockwise movement of yoke 137, which occurs during the first half cycle of operation, as will be explained, studs 135, which extend into cam slots 134 in brackets 132 and 133, are forced nearer to pivotal studs 139, thus moving the tearing knife away from the ribbon as desired.

Fastened rigidly to shaft 131 is a plate 140 (Fig. 7) carrying a pivotal stud 161 which is connected to one end of a link 141. The other end 75

of the link 141 is pivotally connected to a stud 142 on the yoke 137. Raising the link 73 on the first half of the machine operation causes plate 140 to rock clockwise which, through link 141, causes a 5 clockwise movement of yoke 137 on its studs 139, causing the knife to move below the printing line. The second half of the machine cycle reverses the movement of the knife and brings it to the rest position as shown in Fig. 7.

10

Modified form of paper feed

The shaft 131 and plate 140, in addition to actuating the modified knife blade movement, actuate a modified form of paper feed. The paper chute 144 (Figs. 7, 8, and 9) carries the tally strip under the carriage and up to the printing line. The feed mechanism consists of two sets of opposing rollers, between which the paper strip passes, and a means for turning the rollers at each machine 15 operation. These rollers 145 and 170 are mounted at the upturn of the paper chute as shown in Figs. 7, 8, and 9. The upper, idling rollers 145, mounted loosely on shaft 146 (Fig. 8), are yieldingly held against the paper and lower opposing rollers 20 by springs 147 (Fig. 7) and pivoted levers 148 bearing against shaft 146. The lower rollers 170 (Fig. 8) are knurled to better grip the paper and are mounted on shaft 149 which is rotated to provide the feeding action. Mounted on shaft 149 is 25 a toothed driving wheel or ratchet 150 (Figs. 7 and 8) adapted to be turned by machine operated means, to be described, in a counter-clockwise direction, one tooth for every machine operation. This advances the tally strip one line for every 30 machine operation the feeding mechanism is effective.

The driving means for ratchet 150 is actuated by the oscillation of shaft 131 and the plate 140, at each machine operation, which, as before described, is clockwise on the first half of the machine operation and counter-clockwise on the last half of the machine operation. On plate 140 is mounted a driving pawl 151 (Figs. 7, 8, 9 and 10) on pivotal stud 152. The driving pawl 151 is allowed slight oscillation on its pivotal stud limited by a pin 153 (Fig. 9) projecting from plate 140 into a slot 154 cut in the driving pawl. The arc described by point 171 (Figs. 7, 9, and 10) of the driving pawl on oscillation of shaft 131 will vary 50 in radius, said radius being greater when stud 153 is at the top of slot 154 through counter-clockwise rocking of the pawl. The parts are so positioned that the point 171, in moving on the arc of greater radius, engages the ratchet wheel 150, and, in 55 moving on the arc of lesser radius, fails to engage the ratchet wheel.

A locking pawl 155 (Figs. 9 and 10) mounted pivotally on shaft 131 allows ratchet wheel 150 to turn counter-clockwise only. The spring 156 (Figs. 9 and 10) holding the said locking pawl yieldingly against clockwise motion allows the driving pawl to function on the first half of the machine operation, thus advancing the tally-strip before the printing takes place. Spring 156 also 60 acting on driving pawl 151 holds it normally in the effective counter-clockwise position (Fig. 9).

Lever 157, pivotally mounted on driving pawl 151 by a stud 172, as shown in Fig. 9, is for the purpose of turning driving pawl 151 clockwise on pivot 152 against the tension of spring 156, when 65 it is desired to disable the tally paper feed, by causing the point 171 to sweep the arc of lesser radius when moving. To disable the feed, the lever 157 is moved by hand in a clockwise fashion, 70 whereupon the heel 160 (Fig. 9) of lever 157 bears

against an inclined surface 159 on the edge of plate 140 and forces lever 151 clockwise to the limit of movement of stud 153 in slot 154. At this limit of movement, the heel 160 reaches a step in the inclined surface 159 and is retained there, 5 yieldingly, by spring 156 (Fig. 10). The tally feed disabling mechanism will thus stay in the disabling position shown in Fig. 10 until the lever 157 is forced counter-clockwise by hand, against the tension of spring 156, whereupon the parts 10 resume the position shown in Fig. 9.

While in the disabled position, the locking pawl 155 is held away from the position shown in Fig. 9, where it is effective, to the position shown in Fig. 10, where it is ineffective, so that, by manual 15 means to be described, the tally strip may be moved in either direction.

Lying adjacent to and mounted on the same shaft as plate 140 is plate 173 (Figs. 9 and 10) having ears 174 and 175. Plate 173 is mounted 20 loosely on shaft 131 but is limited in clockwise motion, which spring 176 tends to impart, by the ear 175 engaging the upper edge of locking pawl 155. When driving pawl 151 is moved to disabled position its heel 176 (Fig. 10) engages ear 174 of 25 plate 173 and turns plate 173 clockwise, which, through ear 175, forces locking pawl 155 clockwise against the tension of spring 156 and thus allows movement of ratchet 150 in either direction. The shaft 149 is then free to be rotated manually. 30

Modified manual tally roll feed

In the right casing side is mounted a stub shaft 177 (Fig. 11) with a knob 178 (Figs. 8 and 11) secured on its outer end and a gear 179 secured to 35 its inner end. Gear 179 is engaged with a gear 187 mounted on shaft 149. The turning of knob 178 in either direction will move the tally strip forward or backward providing the locking pawl 155 is disabled as described. If locking pawl 155 40 is not disabled, the tally strip may be advanced, only.

In Fig. 11 is shown an arm 180 loosely mounted on stub shaft 177 having a thumb piece 181 pivotally mounted thereon and projecting through 45 a slot 182 in the casing, just below the knob 178, which limits the extent of movement of said arm 180 around 177 as a center. The arm 180 is held in counter-clockwise position by a spring 183. On the other end of the pivotally mounted thumb 50 piece is a pawl 184 adapted to engage the gear 179 when the thumb piece 181 is pushed down and to the rear against the action of spring 183. Release of the thumb piece allows spring 183 to disengage the pawl from the gear teeth and return 55 the arm 180 to the position shown in Fig. 11. Studs 185 and 186 act as stops against movement of the thumb piece when in the position shown in Fig. 11 unless downward pressure is applied to the thumb-piece. The movement of gear 179 by this 60 method causes a rearward movement of the tally strip when it is desired to record on the work sheet alone without tearing off the tally strip.

While the forms of mechanism herein shown and described are admirably adapted to fulfill the 65 objects primarily stated, it is to be understood that it is not intended to confine the invention to the forms or embodiments herein disclosed, for it is susceptible of embodiment in many different forms all coming within the scope of the claims 70 which follow.

What is claimed is:

1. In a tally strip feed mechanism for a machine of the class described, in combination, a tally strip; a printing means; a chute for con-

ducting the tally strip beneath the carriage to a point just beneath the printing line; a means for automatically feeding the tally strip through the conductor chute before the time of printing; 5 means to disable the feeding means; means to manually feed the tally strip irrespective of the automatic feed; a tearing knife located beneath the impression line; and means to move the knife from the path of the impression means while the 10 impression is being made.

2. In a tally strip feed mechanism for a machine of the class described, in combination, a tally strip; a means for recording on said tally strip; a chute for conducting the tally strip beneath the carriage to a point just beneath the recording line; means for automatically feeding the strip through the conductor chute before the time for recording; means to disable the feeding means; means to manually feed the tally strip 15 irrespective of the automatic feed; a tearing knife located beneath the recording line; and means to move the knife from the path of the recording means while the recording is being made.

3. In a tally strip feed mechanism for a machine of the class described, in combination, a tally strip; a printing means; a knife adapted for tearing the used portion of the tally strip from the remainder; means for supporting the knife so as to render the used portion of the tally strip 20 visible to the operator when the machine is at rest; means for removing the knife from the path of the printing means during operation of the machine; means for manually moving the tally strip to a position where it may be torn off against 25 the knife or printed upon; means for automatically moving the tally strip to a position where it may be torn off against the knife or printed upon; means for disabling the automatic means for moving the tally strip; and means for conducting the tally strip to the recording means while the recording is being made.

4. In a tally strip feed mechanism for a machine of the class described, in combination, a tally strip; a means for recording on said tally strip; a knife adapted for tearing the used portion of the tally strip from the remainder; means for supporting the knife so as to render the used portion of the tally strip visible to the operator when the machine is at rest; means for removing the knife from the path of the recording means 40 during operation of the machine; means for manually moving the tally strip any distance step-by-step past the knife and recording means, means for automatically moving the tally strip a certain distance during each machine operation to a position where it may be torn off against the knife or recorded upon; means for disabling the automatic means for moving the tally strip; and means for conducting the strip between the carriage and frame of the machine from rear to front.

5. In a tally strip feed mechanism for a machine of the class described, in combination, a tally strip; a primary work sheet; a means for printing on the tally strip and primary work sheet in one operation; a means for separating the used portion of the tally strip from the remainder, said means being normally positioned to allow all printed data to be seen; means for shifting the tally strip separating means from normal position during a printing operation so as not to interfere with the printing means; means for feeding the tally strip to recording position; and means for stopping the feeding of the tally strip to recording position.

6. In a tally strip feed mechanism for a machine of the class described, in combination, a tally strip; a primary work sheet; a means for recording on the tally strip and primary work sheet in one operation; a means for separating the used portion of the tally strip from the remainder; means for rendering the duplicated work on the primary work sheet visible to the operator when the used portion of the tally strip is separated from the remainder; means for feeding the tally strip to recording position; means for stopping the feeding of the tally strip to recording position; and means for conducting the tally strip to the recording position without blocking the operator's view of the work line and the recorded work.

7. In a machine of the class described having a printing means, a platen for holding record material, and means to move the platen in relation to the printing means so as to permit vertical and lateral spacing of the printed matter on the record material, the combination of a tally strip; a storage device for the unused tally strip; a chute for conducting the tally strip to the printing means independent of the movement of the platen; means intermediate the storage device and the printing means for feeding the tally strip; means to automatically cause the feeding mechanism to feed the tally strip a certain distance each machine operation; manipulative means operable to cause the feeding mechanism to feed the tally strip any desired distance; and means to disable the feeding means.

8. In a machine of the class described having a printing means, a platen for holding record material, and means to move the platen in relation to the printing means so as to permit vertical and lateral spacing of the printed matter on the record material, the combination of a tally strip; a storage device for the unused tally strip; a chute for conducting the tally strip to the printing means independent of the movement of the platen; means intermediate the storage device and the printing means for feeding the tally strip; means to automatically cause the feeding mechanism to feed the tally strip a certain distance each machine operation; manipulative means operable to cause the feeding mechanism to feed the tally strip any desired distance.

9. In a machine of the class described, the combination of printing means; a platen for holding record material to be printed upon; a tally strip mounted separately from the platen; a storage device for the unused tally strip; means intermediate the storage device and the printing means for feeding the tally strip at each machine operation before the printing takes place; and means to disable the feeding means.

10. In a machine of the class described, the combination of printing means adapted to record simultaneously on a work sheet and a tally strip; a storage device for the unused tally strip; means to conduct the tally strip to printing position; means intermediate the storage device and the printing means for feeding the tally strip step by step; automatic means to cause the feeding means to feed the tally strip one step at each machine operation before the printing takes place; manually operated means to cause the feeding means to feed the strip any number of steps without operating the machine; and means to disable the feeding means.

11. In a machine of the class described having cycles of operation, the combination of a print-

- ing means operable each cycle of operation; a platen for holding record material to be printed upon; a tally strip mounted separately from the platen; and a tally strip feed mechanism operable each cycle of operation in advance of the operation of the printing means.
12. In a machine of the class described having cycles of operation, the combination of a printing means operable each cycle of operation; a platen for holding record material to be printed upon; a tally strip mounted separately from the platen; an automatic tally feed means operable each cycle of operation in advance of the operation of the printing means; and a manual tally feed mechanism independent of the automatic means.
13. In a machine of the class described having cycles of operation, a tally strip, a record material carriage adjustable for vertical and lateral spacing of record material held thereby, and a printing means adapted to print on the record material and the tally strip, the combination of a storage device for the unused tally strip located in the rear of the machine so as not to interfere with the operator's view of the printing line; a chute to guide the tally strip to the printing line independent of the carriage; means intermediate the storage device and the printing line for feeding the tally strip; automatic means for causing the feeding means to advance the tally strip a certain distance each machine operation before the printing operation; a manually operable means for causing the feeding means to advance the tally strip independent of the machine operation; and means to disable the feeding means.

14. In a machine of the class described, the combination of a tally strip; a tearing knife against which the used portion of the tally strip may be severed from the unused portion thereof; printing means; and automatic means to move the tearing knife from the path of the printing means during the act of printing and to return the tearing knife to effective position at the conclusion of the printing operation. 5

15. In a machine of the class described, the combination of record material; printing means; means for feeding the record material past the line of impression; a knife having a normal position at the printing line, said knife being used to tear the used portion of the record material 15 from the unused portion thereof; and automatic means to move the knife out of the path of the printing means during the act of printing and to return the tearing knife to effective position at 20 the conclusion of the printing operation.

16. In a machine of the class described, the combination of a printing means; record material; means to move the record material past the line of impression step by step; a knife normally positioned so all the used portion of the record material may be torn off against it, said normal position being in the path of movement of the printing means; and means to automatically remove the knife from the path of movement of the printing means during a printing operation and to restore the knife to normal position at the conclusion of the printing operation. 25 30
